CAPONIZING STRETCHER

Filed Jan. 27, 1930

2 Sheets-Sheet 2

UNITED STATES PATENT OFFICE

MAXWELL C. MERRIFIELD, OF SEATTLE, WASHINGTON

COPONIZING STRETCHER

Application filed January 27, 1930. Serial No. 423,856.

This invention appertains to a novel device for correctly holding a chicken during the caponizing operation and one of the primary objects of my invention is to provide such a device having novel means for clamping the legs of the chicken and novel means for engaging and holding the wings of the chicken with means whereby the leg engaging clamp and the wing engaging clamp can be moved relative to one another so that the chicken can be stretched and properly held in order to be successfully caponized.

A further object of my invention is the provision of novel releasable means for holding the leg clamp and the wing engaging member in adjusted position relative to one another, said means permitting the expeditious adjustment of the clamp and member when desired.

A still further object of my invention is to provide an improved chicken holder or stretcher of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawings, in which drawings:—

Figure 1 is a side elevation of my improved chicken holding or stretching device.

Figure 2 is a top plan view of the same.

Figure 3 is a fragmentary bottom plan view of my improved device illustrating the locking means carried by the wing engaging member.

Figure 4 is a vertical section taken on the line 4—4 of Figure 1 looking in the direction of the arrows illustrating a leg engaging clamp.

Figure 5 is a detail vertical section taken on the line 5—5 of Figure 1 looking in the direction of the arrows showing the stop for the sliding saddle of the wing engaging member.

Figure 6 is a detail section through the device taken on the line 6—6 of Figure 1 illus-

trating the sliding saddle and the locking means therefor.

Figure 7 is a fragmentary longitudinal section taken on the line 7—7 of Figure 6 illustrating the sliding saddle and the lock therefor. 55

Figure 8 is a side elevation of a slightly modified form of my improved chicken holder or stretching device.

Figure 9 is a top plan view of the same, 60 a supporting post for the leg clamp and the wing engaging member being shown in section.

Figure 10 is a detail fragmentary perspective view illustrating the novel lock for the 65 modified form of the device.

Referring to the drawings in detail, wherein similar reference characters designate corresponding parts throughout the several views, the letter A generally indicates my 70 improved chicken holder or stretcher and the same comprises an elongated base rod 15 which may be in the nature of a section of pipe or hollow tube as shown. One end of the base rod 15 supports the leg clamp 16 75 which includes a supporting post 17 having its lower end reduced and threaded and extended into the base rod through a suitable opening formed therein. This reduced threaded end, which is indicated by the 80 reference character 18, may have threaded thereon a holding nut 19, whereby the post is rigidly held in position. The upper end of the post carries the leg clamp per se, which may be in the nature of a resilient wire em- 85

bodying a pair of holding loops 20 and 21, the side legs of which are bowed inwardly as at 22 to provide the restricted neck entrances 23 and then flared outwardly as at 24 so as to guide the legs of the chicken 90 through said neck entrances 23 and into the holding loops 20 and 21. The terminals of the side legs can be provided with suitable heads 25 so as to prevent the forming of points which might injure the operator or 95 chicken. The inner legs 26 of the holding loops are extending inwardly and secured to the extreme upper ends of the posts as shown.

Slidably mounted on the base bar 15 is the saddle block 27, which carries the post 100

28 at its upper end for the wing clamp 29, the wing clamp 29 embodies a pair of diverging resilient wires 30, which have the inner end at the converging portion of the wire 5 secured in any desired manner to the upper end of the post 28. The outer diverging ends of the wires 30 are provided with suitable ball heads 31 so as to prevent the forming of sharp penetrating points.

10 By sliding the saddle 27 on the main bar 15 the wing clamp or engaging member 29 can be moved to or away from the leg clamp for a purpose, which will be later described and means is provided for locking the saddle in 15 any preferred adjusted position on the base bar. This means, as shown, embodies a longitudinally extending rack bar 32 secured to or formed on the lower face of the base bar. In the present instance I have shown 20 the rack bar 32 secured to the base bar 15 by means of fastening elements 33, which extend through reduced ends 34 formed on the rack bar and into the base rod 15.

The lower face of the saddle 27 is slotted 25 as at 35 for receiving the rack bar 32 and the engagement of the side face of the rack bar with the walls of the slot form a guide for the saddle and prevent turning movement of the saddle on the base rod. A pivot 30 ear 36 depends from the saddle on each side of the slot 35 and these ears carry a pivot pin 37 on which is rockably mounted the holding dog 38. The dog 38 is provided at one end with a manipulating handle 39 and 35 at its opposite end a tooth 40 for engaging any selected tooth of the rack bar 32. A leaf spring 41 is provided for normally holding the tooth 40 in engagement with the rack bar as shown in Figure 7 of the drawings.

40 It is to be also noted at this point, that the upper face of the saddle 27 is provided with a boss 42, into which is threaded the lower end of the post 28. A lock nut 43 can be threaded on the post into engagement with 45 the boss for holding the post against displacement.

In use of my improved caponizing device the legs of the chicken are placed within the loops 20 and 21 inward of the lower leg joints 50 as shown in Figure 1 of the drawings. The body of the chicken is now laid on one side or the other of the post 28 and the wings are placed within the wing clamp 29. The saddle 27 is now slid on the base rod 15 away from the leg clamp for effectively stretching and holding the chicken so that the desired operation can be successfully made, the wing clamp 29 holding the wings back and away from the body of the chicken. The chicken 55 can be released by depressing the handle 39 of the dog 38 and sliding the saddle 27 toward the leg clamp.

In order to prevent the movement of the saddle 27 from off of the base rod 15 I provide a stop 45 carried by the end of the base

rod 15 from the end carrying the leg clamp. This stop 45 is in the nature of a plug 46 which is inserted within the base rod 15 and the outer end of this plug 46 is provided with the stop disc or head 47. A fastening bolt or 70 the like 48 is extended through the plug 46 and the base rod 15. Likewise the adjacent fastening screw 33 for the rack bar extends into the said plug.

From the foregoing description, it can be 75 seen that I have provided a novel device for holding a chicken while being caponized which embodies a novel leg clamp and a novel wing engaging member with means whereby the leg clamp and wing member can be adjusted relative to one another to effectively hold and stretch the chicken.

The device can be modified within certain limits and in Figures 8 and 9 I have shown a modified form of my device made of 80 wire and which will be of a cheaper and lighter construction. This form of my invention is generally indicated by the reference character B, and comprises a pair of longitudinally adjustable members 50 and 60. The member 50 carries at its outer end the leg clamp indicated by the reference character 51 which is of the same construction as the leg clamp 16 shown in the first form of my invention and the post of the leg clamp is secured to the outer end of said member 50. The outer end of the member 60 carries the wing clamp, indicated by the reference character 61, which is of the same construction as the wing clamp 29 in the first form. The post 62 of the wing clamp is rigidly connected in any desired way to the outer end of the member 60. The member 50 embodies a pair of spaced parallel longitudinally extending wire or like rods 52, which have the terminals 90 thereof coiled to provide upstanding guide eyes 53.

The member 60 also embodies a pair of spaced longitudinally extending wire or like rods 63 and the inner ends of these wires are coiled to provide depending guide eyes 64. The guide eyes 53 of the member 50 receive the wire rods 63 of the member 60, while the eyes 64 of the member 60 slidably receive the rods 52 of the member 50. By this arrangement, it can be seen that the members 50 and 60 are slidably connected together for longitudinal adjustment and that the leg clamp and the wing clamp can be adjusted relative to one another.

I have provided a simple form of block for 100 adjustably locking these members together and the same embodies a compression loop 70 which receive the rods 52 of the member 50. One end of the loop 70 has pivotally connected thereto the short arm of an operating lever 71 which is rockably mounted as at 72 and adjacent to the loop 70 on suitable pivot ears 73 carried by one of the eyes 64 of the member 60. The lever is provided with an elong- 105

gated manipulating handle 74 which normally extends along the member 60. After the members have been adjusted relative to one another, the lever is pressed inwardly by the hand of the operator which slightly compresses the loop 70 and brings the same into intimate contact with one rod 52 of the member 50 which binds the rod in its guide eye thereby preventing accidental sliding movement of the members. It is obvious that the hand of the operator can grasp the members 50 and 60 and extend around and over the operating handle 74.

Changes in details may be made without departing from the spirit or the scope of this invention, but what I claim as new is:

1. In a caponizing stretcher a wing holder comprising a supporting post and a pair of resilient wire members secured at their inner ends to the post and flaring outwardly therefrom.

2. In a caponizing stretcher, a leg clamp and a wing clamp, means adjustably holding the clamps in any preferred adjusted position relative to one another, the leg clamp embodying a pair of resilient leg receiving loops, and said wing clamp embodying a pair of resilient wires diverging outwardly one from the other.

3. A caponizing stretcher comprising an elongated base rod, a leg clamp rigidly connected to one end of the base rod including a supporting post and leg receiving loops, a saddle longitudinally slidable on the base rod, a post rigidly connected with the saddle, a wing clamp comprising a pair of resilient diverging wires, a rack bar carried by one face of the base rod, the saddle being slotted to receive said rack bar, a spring pressed 40 dog pivotally carried by the saddle for engaging a selected tooth of the rack bar, and a stop carried by the end of the base rod which is remote from the leg clamp.

4. A caponizing stretcher comprising a pair of companion members each including spaced parallel rods, guide means formed on the inner ends of said rods and receiving the adjoining rods of the companion members, leg and wing clamping means carried by said members, a locking lever pivotally mounted upon one of said members, a link straddling the bars of the adjoining member and engaging said locking lever whereby the rods of one member will be brought into binding engagement with the guiding means of the adjoining member for locking the companion members in relative adjusted relation.

In testimony whereof I affix my signature.

MAXWELL C. MERRIFIELD.
